UNITED STATES PATENT OFFICE.

GEORGE SPRICKERHOFF, OF NEW YORK, N. Y., ASSIGNOR OF ONE-HALF TO
THEODORE HAEBLER, OF SAME PLACE.

FIREPROOF STRUCTURE.

SPECIFICATION forming part of Letters Patent No. 623,438, dated April 18, 1899.

Application filed September 20, 1898. Serial No. 691,409. (No model.)

To all whom it may concern:

Be it known that I, GEORGE SPRICKERHOFF, of the city of New York, borough of Manhattan, in the county of New York and State of New York, have invented a new and Improved 5 Fireproof Structure, of which the following is a full, clear, and exact description.

This invention relates to improvements in fireproof structures, such as floors or ceilings; 10 and the object is to provide a structure of this character that shall be light, yet strong in construction, and one that may be readily placed.

I will describe a fireproof structure embodying my invention and then point out the novel 15 features in the appended claims.

Reference is to be had to the accompanying drawings, forming a part of this specification, in which similar characters of reference indicate 20 corresponding parts in all the views.

Figure 1 is a plan view of a fireproof structure embodying my invention. Fig. 2 is a section on the line 2 2 of Fig. 1. Fig. 3 is a section on the line 3 3 of Fig. 1, and Fig. 4 is a 25 perspective view of a stirrup and a portion of a supporting-strip employed in the structure.

Referring to the drawings, 1 designates I-beams as usually employed for supporting floors or ceilings. Attached to opposite beams 30 are stirrups 2, of comparatively light metal, and having their lower portions 3 bent to engage the upper sides, the edges, and the bottoms of the beam-flanges. The vertical portions of the stirrups 2 are provided with vertically-elongated openings 4, into which the 35 ends of metal supporting-strips 5 are placed.

These supporting-strips are of comparatively thin metal. To secure lightness and to give them the necessary strength and rigidity, I 40 turn their top and bottom edges over, the turns being made from opposite sides, as in-

dicated at 6 and 7. Tie-rods 8 are passed through openings 9 in the supporting-strips, and secured to these tie-rods by wires or otherwise is a wire-netting 10, which forms the 45 support for a fireproof cement or concrete 11, which should fill the space between the netting and the top of the beams.

While I have shown the stirrups as attached to the lower portions of the beams, it is obvious 50 that they may be secured to the upper sides and extended downward.

Having thus described my invention, I claim as new and desire to secure by Letters Patent—

55

1. In a fireproof structure, the combination with beams, of stirrups attached to said beams, supporting-strips supported by opposite stirrups, tie-rods extended through openings in the strips, a netting secured to the tie-rods, 60 and cement on the netting, substantially as specified.

2. In a fireproof structure, the combination with beams, of stirrups attached to said beams, supporting-strips having their ends engaged 65 in openings in opposite stirrups, tie-rods extended through openings in the strips, netting secured to the tie-rods, and cement on the netting, substantially as specified.

3. In a fireproof structure, the combination 70 with beams, of stirrups having portions engaged around flanges of the beams, supporting-strips having their top and lower edges turned over in opposite directions, the said strips being supported in the stirrups, netting supported by said strips, and cement on the netting, substantially as specified. 75

GEORGE SPRICKERHOFF.
